(No Model.)

W. H. REIFF.
TOY TARGET.

No. 451,725.

Patented May 5, 1891.

UNITED STATES PATENT OFFICE.

WILLIAM H. REIFF, OF PHILADELPHIA, PENNSYLVANIA, ASSIGNOR OF ONE-HALF TO J. WALKER CLARK, OF SAME PLACE.

TOY TARGET.

SPECIFICATION forming part of Letters Patent No. 451,725, dated May 5, 1891.

Application filed February 3, 1891. Serial No. 380,066. (No model.)

To all whom it may concern:

Be it known that I, WILLIAM H. REIFF, of the city of Philadelphia, county of Philadelphia, and State of Pennsylvania, have invented an Improvement in Toy Targets, of which the following is a specification.

My invention relates to toy targets; and it consists of certain improvements which are fully set out in the following specification and are shown in the accompanying drawings, which form a part thereof.

The object of my invention is to produce a device for purposes of amusement which shall call forth the exercise of more or less skill upon the part of the operator.

In carrying out my invention I employ a suitable supporting-piece having one or more apertures or recesses formed therein, adjacent to which are placed object balls or buttons.

The object of the device is to strike these object balls or buttons and knock them into the apertures or recesses by means of a captive ball connected with the supporting-piece by an elastic connection. By employing a series of these object balls or buttons and appropriate apertures therefor shots of different degrees of difficulty may be obtained.

In the drawings, Figure 1 is a plan view of my target apparatus. Fig. 2 is a longitudinal sectional view of the same on the line $\alpha\alpha$ of Fig. 1. Fig. 3 is a perspective view of a portion of the same, and Fig. 4 is a plan view similar to Fig. 1 of a modification of my invention, employing a series of object balls or buttons.

A is a suitable supporting-piece, preferably flat, which may be made of card-board or any other convenient material. B is an aperture formed therein and provided with a notch b. C is an object ball or button, which is connected with the back of the piece A by a connection D. The object ball or button C is supported in the notch b, as shown in the drawings, so as to be exposed upon the face of the supporting-piece A.

E is a captive ball, connected with the piece A by means of an elastic connection F. By extending and then releasing the elastic connection F the captive ball E will be projected forward toward the object C, and if properly

aimed will strike the object and knock it from the notch b through the aperture B. It will be found that more or less skill is required to properly aim the captive ball E.

For convenience of construction I prefer to attach the object ball or button C to the piece A in the manner shown—*i. e.*, by means of an elastic band, which may be attached to the piece A by passing the loops of the band D through clips a a, formed in the piece A. The elasticity of the band D tends to draw the ball or button C through the aperture B, when it is released from the notch b.

In Fig. 4 a modification of my apparatus is shown, in which there are a series of apertures B, preferably arranged in curve or arc of a circle, with an appropriate object ball or button C for each aperture supported by the elastic band D. Different degrees of skill will be required to strike the differently-situated objects C with the captive ball E, and it calls forth the exercise of considerable skill to strike all of the objects in succession which may be made the object of the game.

While the minor details of construction, which have been shown are preferred, it is apparent that they may be varied without departing from the principles of my invention.

What I claim as new, and wish to secure by Letters Patent, is—

1. A target-game apparatus consisting of a supporting-piece provided with one or more notched apertures or recesses, an object ball or button attached to said supporting-piece and supported in the notch of the aperture therein, and a captive ball connected with said supporting-piece by an elastic connection, substantially as and for the purpose specified.

2. In a target-game apparatus, the combination of a supporting-piece provided with a notched aperture, an object ball or button connected with one side of said supporting-piece and adapted to be supported in the notch of said aperture and presented upon the other side thereof, and a captive ball connected with said supporting-piece by an elastic connection, substantially as and for the purpose specified.

3. In a target-game apparatus, the combination of the supporting-piece A, provided with one or more apertures B, having notches b, one or more object balls or buttons C, 5 adapted to be supported in the notches b, elastic connection D, connecting said object balls or buttons with the piece A, captive ball E, and elastic connection F, connecting the

captive ball with the piece A, substantially as and for the purpose specified.

In testimony of which invention I have hereunto set my hand.

WILLIAM H. REIFF.
